UNITED STATES PATENT OFFICE

JOSEPH BEHLE AND CHRISTIAN W. HODDE, OF DALLAS, TEXAS, ASSIGNORS TO THE MURRAY COMPANY, OF DALLAS, TEXAS, A CORPORATION OF TEXAS

HEAT TREATING MACHINE

Application filed January 16, 1931. Serial No. 509,119.

This invention relates to new and useful improvements in heat treating machines.

One object of the invention is to provide a machine for automatically heating gin ribs and similar articles.

A further object of the invention is to provide a machine for heating an isolated or restricted portion of the rib and particularly for concentrating the heating flame on said restricted portion.

Another object of the invention is to provide a machine for progressively heating a restricted section of a gin rib, whereby a rib may be fed to the machine, heated and discharged therefrom, and a plurality of ribs heated successively, thus making for a continuous operation.

A still further object of the invention is to provide means for automatically progressing the ribs, whereby the duration of the heating period over each flame is automatically controlled.

A construction designed to carry out the invention will be hereinafter described together with other features of the invention.

The invention will be more readily understood from a reading of the following specification and by reference to the accompanying drawings in which an example of the invention is shown, and wherein:

Figure 1 is a plan view of a machine constructed in accordance with the invention, Figure 2 is an end elevation of the same,

Figure 3 is a vertical sectional view taken on the line 3-3 of Figure 1,

Figures 4 and 5 are details of the rib carriers,

Figure 6 is a vertical sectional view of the motor and gear case, and

Figure 7 is a vertical sectional view taken on the line 7-7 of Figure 6.

In the drawings the numeral 10 designates the vertical front plate of a supporting structure or frame. The plate has a forwardly extending base 11 from which inclined braces 12 rise to the top of the plate.

The plate is spaced from and connected to the front wall of a vertical gearing case 13 by bridle bars 14.

A drive shaft 15 extends through the front

wall of the case and has fastened thereon a drive sprocket 16. An endless sprocket chain 17 travels around this sprocket and also around an idler sprocket 18 mounted on said wall at the opposite end of the case. This chain 17 will be called the upper chain.

A driven shaft 19 also extends through the front wall of the case 13 below the shaft 15 and has its forward end journaled in a bearing box 20 on the front wall 10. A sprocket wheel 21 is fastened on said shaft adjacent the inner side of the wall 10. This sprocket drives an endless sprocket chain 22 which is also carried by a sprocket wheel 23 journaled on a box 24 at the opposite end of the front plate 10.

The upper sprocket chain 17 has carriers 25 attached to its links (Figure 5) and each shaped to receive the upper end of a gin rib, while the lower chain 22 is provided with 70 sockets 26 each shaped to snugly receive the lower end or foot of a gin rib (Figure 4). A hanger 27 is spaced from the gear case 13 in front of the upper sprocket chain 17 and supported by studs 28 and an end bracket 29 secured to the end of the case 13. Burner tubes 30 are mounted in the bracket and provided with tips 31 at their upper ends. These burner tubes are held in position near their lower ends by a spacer bar 32 and each is 80 connected to a Y-coupling 33 below the bar.

A gas feed pipe 34 is attached to one leg of the Y-coupling and an air pipe 35 is attached to the other leg of the Y-coupling and these pipes include suitable control valves. The gas pipe 34 is connected with a gas supply manifold 36 which is connected at one end with a gas supply pipe 37. The pipes 35 are connected with an air manifold 38 which is supplied with compressed air from a suitable source through a pipe 39.

A proper mixture is supplied for producing a narrow vertical flame above each tip 31. This flame is very important and may be of the needle type so as to restrict its active area. The gin ribs A are placed in the carriers 25 and 26, as is shown in Figures 1, 2 and 3 and these carriers are so spaced as to position each rib directly over one of the tips. Each gin rib is formed with a wear 100

boss B and when the ribs are assembled in the gin these bosses are located between the saws at the points where the lint passes through so as to compensate the abrasion at this point. The flames are concentrated on these bosses and the heat thus concentrated thereon. While the adjacent portion of the rib will be heated by conductivity the application of direct heat is limited to the boss.

We have shown six burner tubes and means which will be hereinafter described is provided for periodically propelling the chains so that the ribs are progressively heated and by the time a rib reaches the last burner to the right (Figure 3), it will have been heated to the proper degree and will be ready for quenching, which may be done in a suitable vat in any convenient manner. Adjacent the sprocket 23 is mounted an ejector 40. This ejector may be supported on the box 24 on which the sprocket 23 is loosely mounted.

The ejector 40 has a curved shoe 41 at its upper end so shaped and so located as to dislodge the lower end of the gin rib from the carrier 26. An ejector shoe 42 is formed on the upper end of the bracket 29 and so located as to be engaged by the upper portion of the rib when the lower portion engages the shoe 41. These ejector shoes will dislodge the ribs from the carriers as they start downward around the sprockets 18 and 23. The discharged ribs may be caught in any suitable way. The ribs are fed to the machine by placing them in the carriers 25 and 26 at the left hand end (Figure 3) of said machine.

Above the burner tips 31 and also above the ribs, we provide a heat deflector 43 formed of fire clay or any equivalent material and having a dome 44 immediately over each tip. The deflector is mounted in a hanger 45 suspended from brackets 46 mounted on the gear case 13. The domes 44 will tend to deflect the heat from the flames downward on top of the bosses B and thus thoroughly heat the same. A guard 47 is mounted on the front plate 10 between the sprocket wheels 21 and 23 and a similar guard 48 is mounted under the top of the chain 17 on the front of the case 13. The vertical face of the hanger 27 is provided with a facing 27' of sheet asbestos, or other fire-resisting material.

In the gear casing 13 an electric motor 50 is mounted on a shelf 49 and has a gear 51 mounted on its shaft. This gear drives a second gear 52 mounted on a shaft 53 journaled in the gear case. A cam 54 is fastened on the shaft 53 and a tripping lever 55 has a roller 56 (Figures 6 and 7) travelling on the periphery of the cam. The lever 55 is pivoted on a shaft 57 and has one end attached to a coiled spring 58 which surrounds said shaft and has its opposite end attached to a collar 59 fixed on said shaft. The spring is coiled

so as to exert a tension and constantly hold the roller 56 in engagement with the cam.

On its opposite end the lever has a spring-pressed pawl 60 adapted to engage the teeth of a ratchet 61, which is fastened on the shaft 15 of the upper sprocket 16. A pinion 62 is also fastened on this shaft and drives a pinion 63 fastened on the shaft 19 by means of an intermediate pinion 64 mounted on a stub shaft 65. The pinions 62, 63 and 64 are of the same diameter and consequently the shaft 19 will be driven in the same direction and at the same rate of speed as the shaft 19.

The teeth of the ratchet 61 are so spaced that upon each operation of said ratchet the sprocket chains will be moved a sufficient distance to step each carrier from its position over one burner to a position directly over the next burner. While the roller 56 is traveling on the concentric face of the cam 54 the lever 55, and consequently the chains, will be at rest, and this will be the heating period. When the roller dips into the crotch of the cam the lever 55 will be swung, whereby the pawl will be lifted and engaged with the next tooth. Thus, when the roller rides out of the crotch the lever will be swung thus advancing the ratchet 61 and propelling the chain. It is obvious that changes could be made in the timing mechanism and the propelling mechanism.

Various changes in the size and shape of the different parts, as well as modifications and alterations, may be made within the scope of the appended claims.

Having illustrated and described a preferred form of the invention, what we claim is:

1. In a heat treating machine, a frame, a pair of endless chains journaled in the frame in spaced substantially parallel order, carriers mounted on the chains for receiving the ends of elongated metal articles, vertical burners, means for supporting the burners in spaced order between the chains and substantially parallel thereto, means for imparting a step by step movement to the chains in unison, means for disengaging the articles from the carriers, and a deflector mounted above the burners.

2. In a machine for heat treating the wear bosses of gin ribs, a plurality of burners successively arranged and each having means for producing an elongated vertical needle-like flame, and a conveyor having means for carrying a plurality of ribs spaced in corresponding order to the burners for positioning the wear boss of each rib directly over and at a substantial distance above one of the burners, whereby all of the rib bosses are positioned over burners at the same time and also whereby the elongated flames are confined to said wear bosses.

3. In a machine for heat treating the wear bosses of gin ribs, a plurality of burners successively arranged and each having means

for producing an elongated vertical needle-like flame, a conveyor having carrying elements for supporting gin ribs in an upright position and spaced so that the wear bosses of the ribs will be located directly over the burners when said conveyor is stopped, and means for intermittently operating the conveyor.

4. In a machine for heat treating the wear bosses of gin ribs, a supporting structure, a pair of spaced endless chains movably mounted on said structure, one of said chains being at a higher elevation than the other, a plurality of burners mounted between the chains and longitudinally thereof, said burners having means for producing elongated vertical needle-like flames, means on the chains for supporting gin ribs in upright positions with their wear bosses directly over said burners, means on the structure for operating said chains, and means for deflecting the heat from the burners down onto the wear bosses of the ribs.

In testimony whereof we affix our signatures.

JOSEPH BEHLE.
CHRISTIAN W. HODDE.
